UNITED STATES PATENT OFFICE.

JOHN H. DEPELER, OF WEEHAWKEN, NEW JERSEY, ASSIGNOR TO METAL & THERMIT CORPORATION, OF CARTERET, NEW JERSEY, A CORPORATION OF NEW JERSEY.

METHOD FOR FORMING SLAG-FREE THERMITE WELDS.

Application filed July 16, 1925. Serial No. 43,916.

The invention relates to the forming of slag free thermite welds and comprises a novel method of forming such welds and a special form of mold for carrying out the method.

Apparatus for carrying out the method is illustrated in the accompanying drawing, in which:

The figure is a sectional elevation of a special mold.

It has been the general practice in welding miscellaneous pieces, such as locomotive frames, crank shafts and similar large castings, by the thermite method, to employ 15 large molds using great quantities of molding material and having long runners or pouring gates leading the liquid thermite metal into the bottom of the mold space at or near the bottom of the parts to be welded, 20 the pouring gate usually being disposed at an angle to the vertical. Similarly, in rail welding by the thermite method, the pouring gate was long and oblique leading the liquid steel into the mold about the base 25 of the rail.

Recently, however, it has been found desirable, for the purpose of reducing the cost of thermite welding, and more completely eliminating blow holes and similar 30 defects from the welds, to greatly reduce the size of the mold and, therefore, the amount of molding sand used, and, as a consequence of this, the runners or pouring gates have necessarily been made shorter, less oblique 35 or more nearly vertical. Likewise, in welding certain types of rails, it has been found advantageous to dispose the pouring gate in the top of the mold adjacent the gauge faces of the rails and substantially in vertical alignment with the space between the rail ends.

It was not anticipated in either of these practices that the shortening of the pouring gate and the disposition of the same, either 45 vertically or approximately vertically, would produce any harmful or objectionable effects, but it was frequently noticed that slag was found entrapped in the welds produced with molds of the types indicated. 50 This objectionable phenomenon was especially noticeable in rail welding involving the use of an insert between the rail ends adjacent the tread portions, as slag was almost invariably trapped under the insert. Vari-

ous expedients have been tried for the purpose of overcoming this defect, such as beveling the under side of the insert to form a more or less abrupt angle with the horizontal in the hope and expectation that this would permit the slag to rise along the 55 inclined or beveled surfaces and pass off through the riser, leaving nothing but clean thermite steel under the insert, without the intervening layer of slag, which prevented fusion of the metallic parts wherever such 60 slag was present. Neither this nor other expedients, which have been tried, obviated the difficulty until the instant invention was 65 developed and successfully applied.

In thermite welding, a bottom pour crucible is suspended over the top of the pouring gate of the mold and in this crucible the thermite reaction forms simultaneously a certain weight of liquid steel and a commensurate weight of molten slag, the steel 70 going to the bottom of the crucible and the slag rising to the top. When the crucible is tapped by dislodging the plug or pin in the bottom opening thereof, the thermite steel enters the mold space through the pouring gate directly below the tap-hole in the crucible and on top of the steel the slag falls, 75 and, although this slag is of only approximately half the density of the steel already 80 teemed in the pouring gate and the mold space, it nevertheless, because of its momentum, strikes the top of the molten steel in the gate with sufficient force to depress the metal and permit some of the slag to enter the mold space, where, due to its characteristic tendency to adhere to steel, it 85 coats or forms a film over the ends of the pieces to be welded, or, in the case of rail welding, is trapped under the insert, and, 90 although the steel surges back quickly, it 95 cannot force out the slag which has adhered to the surfaces or has been thus trapped, and the weld is irreparably damaged.

I have discovered, however, that by diverting the slag containing portion of the molten 100 charge from direct falling contact with the molten steel in the gate and directing this portion of the charge against a surface of the mold adjacent to the pouring gate and at an angle to the axis of the pouring gate, the momentum of the charge will be dissipated by the impact against such surface 105 and this portion of the charge will flow

quietly into the gate, so that no portion of the slag will reach the mold cavity or the parts to be welded enclosed therein.

A relatively simple arrangement to effect this highly desirable object is illustrated in the accompanying drawing, in which 1 indicates the mold as a whole, 2 the mold cavity therein into which the ends of the parts to be welded extend, 3 the riser, 4 the heating gate, and 5 the pouring gate. Near the upper end of the latter, one of the walls is diverted laterally to form a relatively flat angle with the longitudinal axis of the gate, forming an inclined surface 6 against which the molten thermite charge T is directed, by positioning the crucible C so that the bottom tap-hole thereof is vertically above such surface 6, whereby the force of the falling stream of slag and metal is practically dis-

sipated and the molten mass flows quietly 20 into the gate.

It will be understood that the particular arrangement and disposition of the impact surface 6, as described, is merely exemplary and may be changed or varied to suit the 25 particular conditions and, in fact, such impact surface may be located in the top surface of the mold proper adjacent to and leading into the pouring gate.

What I claim is:

The method of forming slag free thermite welds in molds which comprises teeming the slag containing portion of said charge against a surface of the mold adjacent the entrance of the pouring gate, whereby the 35 force of the falling charge is dissipated.

In testimony whereof I affix my signature.
JOHN H. DEPELER.
